UNITED STATES PATENT OFFICE.

OSCAR J. MENDENHALL, OF GIBBON, NEBRASKA.

DEVICE FOR REMOVING TIES FROM RAILROAD TRACKS.

Application filed October 3, 1921. Serial No. 505,163.

To all whom it may concern:

Be it known that I, OSCAR J. MENDENHALL, a citizen of the United States, residing at Gibbon, in the county of Buffalo and 5 State of Nebraska, have invented new and useful Improvements in Devices for Removing Ties from Railroad Tracks, of which the following is a specification.

The invention relates to a device for removing ties from railroad tracks.

The object of the present invention is to provide a simple, practical and efficient device designed for removing ties from railroad tracks and capable of being readily 15 arranged in position for engaging the rails and a tie beneath the same, and easily and entirely removing the tie from its position beneath the rails without digging the tie from the roadbed.

With these and other objects in view the invention consists in the novel construction, combination and arrangement of parts hereinafter fully described, illustrated in the accompanying drawings and pointed out in 20 the claims hereto appended, it being understood that various changes in the form, proportion and minor details of construction within the scope of the claims, may be resorted to without departing from the spirit 25 or sacrificing any of the advantages of the invention.

In the drawing in which like characters of reference designate the corresponding parts in the several views:—

Figure 1 is a plan view of a device constructed in accordance with this invention for removing ties from railroad tracks.

Figure 2 is a longitudinal sectional view of the same.

Figure 3 is a transverse sectional view of the device.

In the accompanying drawing, in which is illustrated the preferred embodiment of the invention, the device for removing ties 45 from railroad tracks comprises in its construction a ratchet bar 1 having a flat lower face to enable it to be arranged upon the upper face of a tie 2, longitudinally thereof and provided at its upper face with shoulders or teeth 3 formed by recesses 4 and adapted to be engaged by an actuating dog 5. The recesses 4 form incline faces which are presented to the rails in passing beneath the same and the teeth will not interfere 55 with the longitudinal movement of the ratchet bar in the operation of removing

the cross-tie and in practice the spikes will be removed from the cross-tie and the rails lifted sufficiently to enable the ratchet bar to be introduced between the rails and the cross-tie. The ratchet bar is provided at its rear end with a longitudinal stud 6 threaded at its outer portion to receive a nut 7 for retaining a tie engaging plate 8 on the stud. The tie engaging plate, which is loosely pivoted to the end of the ratchet bar by the stud, depends below the ratchet bar and engages the end of the tie as clearly illustrated in Figure 2 of the drawing.

The dog 5 which has a tapered engaging outer portion 9 is pivoted at its inner end by suitable pivot 10 to an operating lever 11 fulcrumed intermediate of its ends in a frame on a transverse pin or pivot 12. The lever, which extends through the said frame, is provided in its lower end with a slot or bifurcation 13 to receive the pivoted end of the dog and the upper portion of the operating lever serves as a handle for operating the device.

The frame in which the operating lever is mounted is composed of spaced parallel side bars 14 connected at their ends by cross pieces 15 and provided at their lower edges with terminal recesses 16 forming shoulders 85 for engaging the rails 17. The cross pieces 15 which connect the side bars of the frame are located at the upper faces of the said side bars but they may be arranged in any other desired manner, and the frame which 90 is oblong extends across the rails 17 and the shoulders formed by the recesses 16 fit between the rails and engage the same at the inner sides thereof. By this arrangement the oblong frame is firmly anchored upon 95 the track and the operator, who preferably stands upon the frame, is enabled to readily apply the necessary power to the long upper operating arm of the lever for removing the cross-tie. As the ratchet bar is separate 100 from the frame and as the lever is located at one side of the center of the device so that the dog, in the operation of the device, will extend to a position beneath the adjacent rail, it will be clear that the tie may be entirely removed from the roadbed by the device through the successive oscillations of the operating lever. The teeth or shoulders of the ratchet bar are successively engaged 105 by the dog and the tie is removed from the roadbed by a step by step movement until it is forced entirely from its position be-

neath the rails. This obviates the necessity of digging out cross-ties when it is necessary to remove the same.

What is claimed is:—

5. 1. A device for removing railroad ties from tracks, comprising a frame having means for engaging the rails of a track, a ratchet bar located beneath the rails and unattached to and spaced out of alignment with the frame by the rails and adapted to be supported upon a tie and provided with means for engaging one end thereof, said ratchet bar being provided with teeth, a lever fulcrumed in the frame and a dog carried by the lever and arranged to engage the teeth of the ratchet bar.
10. 2. A device for removing ties from railroad tracks, comprising a substantial oblong frame provided with side bars adapted to be arranged upon the rails of a track and provided with shoulders or engaging portions extending below the treads of the rails and engaging the same at the inner sides thereof,
15. 3. A device for removing ties from railroad tracks, comprising a frame extending across the track and having rail engaging means, a lever fulcrumed in the frame, a ratchet bar located beneath the rails and unattached to the frame and spaced out of alignment with the latter by the rails and provided at one end with a stud, a plate pivoted to the ratchet bar by the said stud and depending therefrom to engage the end of a cross-tie, and means carried by the lever and extending under one of the rails for engaging the teeth of the ratchet bar.

In testimony whereof I have hereunto set my hand.

OSCAR J. MENDENHALL.
